UNITED STATES PATENT OFFICE.

HARRY BENSON, OF ALAMEDA, CALIFORNIA.

SLIDING-DOOR LOCK.

1,381,271.

Specification of Letters Patent. Patented June 14, 1921.

Application filed December 24, 1919. Serial No. 347,203.

To all whom it may concern:

Be it known that I, HARRY BENSON, a citizen of the United States, residing at Alameda, in the county of Alameda and State 5 of California, have invented new and useful Improvements in Sliding-Door Locks, of which the following is a specification.

The present invention relates to improvements in locks for sliding doors, particularly elevator-doors and the primary object of the invention is to provide a lock which when the door is moved into closed position, will automatically lock the door or when the door is nearly but not completely closed or 15 when closed and the lock for any reason fails to operate, will likewise lock the door against opening.

In some States the laws concerning elevator doors require that the door must lock 20 when closed and also lock if only moved to within a few inches of closing position for example three inches. My invention contemplates the provision of a lock which will operate within such laws. I am aware of 25 locks which lock when the door is closed and also lock when the door is brought within a few inches of being closed, but in locks of this type it is possible for meddlesome or curious persons, or vandals to reach in behind or through the door, and unlock and then open it farther. With my lock it is impossible to open the door as above outlined since it is necessary to close the door 30 when it is locked against opening in position short of being completely closed, before it can be opened. Thus, this practice of putting the hand or an instrument between the door or through the door and jamb and 35 unlocking and opening the door is prevented and many accidents such as occur when elevator doors are left open will be avoided.

Another object of my invention is to provide a relatively simple, inexpensive, and highly efficient and reliable lock of the character described which may be easily installed, will take up little room and which can be easily operated and controlled.

The invention possesses other advantages and features, some of which, with the foregoing will be set forth at length in the following description where I shall outline in full, that form of the invention which I have selected for illustration in the drawings accompanying and forming a part of the present specification. In said drawings I have shown one form of the construction

of my invention but it is to be understood that I do not limit myself to such form, since the invention as expressed in the claims may be embodied in a plurality of forms. 60

Referring to the drawings:

Figure 1 is a front elevation of an elevator door unit showing my invention applied thereto and in dotted lines as it would appear when the door is open. 65

Fig. 2 is a sectional view taken on line 2-2 of Fig. 1. 65

Fig. 3 is a front elevation of the locking mechanism of my invention.

Fig. 4 is a vertical sectional view taken 70 through the locking device showing the mechanism in the locked position assumed when the door is not fully closed but partially closed, also showing the door operating lever free and in unlocked position in 75 dotted lines.

Fig. 5 is a fragmentary vertical sectional view of the lock showing the mechanism in positively locked position and also showing the locking member in releasing position in dotted lines. 80

Fig. 6 is a cross sectional view taken on line 6-6 of Fig. 3.

Referring to the drawing 1 designates a frame for an elevator door unit in which are 85 mounted a stationary section of grating 2, and sliding doors 3 and 4. The doors are suspended on rollers 5 which ride on a track 6 extending along the top of the frame 1.

The door 3 is the outer door, and abuts the 90 jamb 7 whereas the door 4 is the inner door and is connected with the door 3. This construction is commonly used in the majority of office buildings and need not be further described. A door operating lever 8 is pivoted as at 9 to the sill or floor of the building behind the grating 2 and is slidably connected with both doors. A roller 10 is carried on the lever at a point approximately centrally of the ends thereof and is 95 arranged to move vertically in a guide 11 therefor on the inner door 4. A similar guide 12 is carried on the door 3 and receives a flanged roller 13 carried on the outer end of the lever. Through this interconnection 105 when the door 3 is opened it will move a distance substantially equal to its width before the door 4 will begin to open and this operation is likewise the case in shutting or closing the doors. This operation is common to 110 elevator doors now in general use and need not be described in detail.

- The means for locking the doors in closed position automatically when the doors are fully closed comprises a latch handle 14 of spring metal, one end of which being extended as at 15, and fastened as at 16 to the guide 12, leaving the handle portion free to be pulled outwardly away from the door against the inherent spring action of the extended portion.
- Secured to the handle 14 is a latch lug 17 which extends through an opening 18 in the guide 12 into the path of the roller 13. The upper face of this lug 17 is curved downwardly and inwardly to allow the roller to force the lug outwardly and to move past and below the lug. The lower face is flat and acts as a stop to prevent the roller 13 from being moved past the lug.
- Means for preventing opening of the door when the door has not been closed sufficiently to be locked by the lug 17 but has been brought to within approximately three inches of closing position, comprises a latch-lug 19 carried by leafspring member 20 on the portion 15 of the handle 14. The member 20 is fixed at one end to the portion 15 as at 21 and carries the lug 19 near its free end. This end is provided with a slot 22 in which a leaded stop 23 on the handle 14 is extended. This stop limits the movement of the member 20. The lug 19 extends through an opening 24 in the guide 12, into the path of the roller 13. The upper face of this lug is beveled as at 25 to permit the roller to be forced past the lug. This lug 19 is so arranged above the lug 17 that the degree of movement permitted the roller 13 when between these lugs will be such as would allow the door 3 to be opened only a slight distance, such as three inches, or to be fully closed. The movement of withdrawing the lug 17 also withdraws lug 19.
- I provide means for locking the latch handle 14 against being operated to withdraw the latch lug 19, when the roller 13 is between the lugs 17 and 19 and the door is locked against opening in partially but not fully closed position. This means prevents the door from being opened by unauthorized, careless or meddlesome persons, from the outside and requires that the door be first fully closed before the latches 17 and 19 may be withdrawn and the door opened. This means preferably comprises a plunger 26 vertically movably mounted in a cylinder 27 which is suitably supported at the lower extremity of the guide 12. An expansion spring 28 is disposed between the lower end of the cylinder, and the plunger so as to hold the plunger in extended position normally. The upper end of the plunger is bifurcated as at 29 so as to receive the lug 17 and slide past said lug as shown in Fig. 4 of the drawings. A locking bolt 30 is slidably transversely through the cylinder 27 and is fixed at one end as at 31 to the latch handle 14. A stop member 32 is mounted on the other end of the bolt to prevent withdrawal thereof from the cylinder 27. The plunger is cut away as at 33 on one side thereof so as to be able to slide up and down past the bolt. A shoulder 34 is formed adjacent to the lower end of the plunger at the lower termination of the cut away portion and is adapted to contact with a shoulder 35 formed by recessing the bolt 30. These shoulders coact when the roller 13 is free of the latch lug 17 and the plunger is in up position. When these shoulders coact the bolt 30 cannot be moved and this holds the latch handle 14 against movement.
- In operation, when the door is being closed the flanged roller 13 moves into engagement with the latch lug 19, forces said lug outwardly against the spring action of the member 20 and moves past said lug and engages and passes the lug 17. The lug 17 will snap back into place and latch the roller 13. The roller thus held (see Fig. 5) prevents movement of the lever 8 and both the doors 3 and 4 are locked in closed position. As the roller 13 approaches the lug 19 it engages and pushes down the plunger 26. The plunger is thus held down while the door is locked by the lug 17 and the shoulder 34 on the plunger 26 is moved out of engagement with the shoulder 35 on the bolt 30, as shown in Fig. 5. The bolt is then free to slide and by grasping and pulling out on the handle 14 the latch lugs 17 and 19 will be withdrawn and the roller 13 being free to move in the guide 12, permits the doors to be opened in the ordinary manner. Should the door not be fully closed but nearly so the roller will move past the lug 19 and as it is then prevented from moving back as in opening the door, by said lug, the door is locked against further opening movement but may be moved so as to close.
- When the roller 13 is in this position, as shown in Fig. 4, the plunger 26 is held in "up position" by the spring and the shoulders 34 and 35 on the plunger and bolt coact so that the bolt and handle 14 connected with the bolt cannot be moved. As the handle cannot be moved the lug 19 cannot be withdrawn, so it is therefore impossible to unlock and open the door without releasing the latch handle 14. To release the handle, the door is closed and the roller 13 will depress the plunger 26. When the plunger is depressed the bolt 30 is free to slide and the handle may be pulled out to withdraw the lugs 17 and 19. The door is then free to be opened.
- I claim:
1. The combination with a door frame and a door therein, of means for locking the door against opening in partly closed and fully closed positions respectively, means

for releasing said locking means, and means for preventing release of said locking means while the door is locked in partly closed position.

5 2. The combination with a door frame and a sliding door in said frame, of means for locking the door when the latter is moved into closed position, means for locking the door against opening in partly closed position when the door fails to close but moves past a predetermined point, means for releasing both of said locking means, and means for holding the releasing means against operation while the door is

15 locked against opening in partly closed position.

3. The combination with a door frame, and a sliding door in said frame, of means for locking the door when the latter is moved into closed position, means for locking the door against opening in partly closed position when the door fails to close but moves past a predetermined point, means for releasing both of said locking

25 means and means which when the door is locked in partly closed position will hold the releasing means against operation and when the door is moved into closed from partly closed position will release the re-

30 leasing means.

4. The combination with a door frame and a door therein of means for automatically locking the door in closed position, means which will automatically lock the door against opening when the door fails to close but moves past a predetermined point, means for releasing both said locking means and means for automatically holding the releasing means against operation when the door is locked in partly closed position and for releasing said releasing means when the door is locked in closed position.

5. The combination with a door frame and a door slidably mounted in the frame, of a lever pivoted to the frame, a guide on the door, a member on the lever and mounted to slide in said guide during movement of the door, means to lock said member against movement when the door is closed, means for locking said member against movement such as will cause the door to open when the door fails to close and is moved into partly closed position, means for withdrawing and releasing both said locking means, and means for holding the withdrawing and releasing means against operation when the door is locked in partly closed position.

60 6. The combination with a door frame and a door slidably mounted in said frame of a lever pivoted to the frame, a guide on said door, a member on the lever which is mounted to slide in said guide during movement of the door, a latch lug extending into

the path of said member for preventing movement of the member when the door is closed, a latch handle upon which the lug is mounted fixed to the door for movement toward and away therefrom, a latch lug 70 connected with the handle extending into the path of said member for preventing movement thereof to open the door when the latter is brought into nearly closed position and means which will lock the handle 75 against operation when the door is locked in partly closed position and unlock said handle when the door is locked in closed position.

7. The combination with a door frame 80 and a door slidably mounted in said frame of a lever pivoted to the frame, a guide on said door, a member on the lever which is mounted to slide in said guide during movement of the door, a latch lug extending into 85 the path of said member for preventing movement of the member when the door is closed, a latch handle upon which the lug is mounted fixed to the door for movement toward and away therefrom, a latch lug 90 connected with the handle and extending into the path of said member for preventing movement thereof to open the door when the latter is brought into nearly closed position and means which will lock the handle 95 against operation when the door is locked in partly closed position and unlock said handle when the door is locked in closed position, said lugs being beveled on their upper faces to permit the member to move 100 past the lugs during the closing movement of the door.

8. The combination with a door frame and a door slidably mounted in said frame of a lever pivoted to the frame, a guide on 105 said door, a member on the lever which is mounted to slide in said guide during movement of the door, a latch lug extending into the path of said member for preventing movement of the member when the door is 110 closed, a latch handle upon which the lug is mounted fixed to the door for movement toward and away therefrom, a latch lug connected with the handle, and extending 115 into the path of said member for preventing movement thereof to open the door when the latter is brought into nearly closed position and means which will lock the handle against operation when the door is locked in partly closed position, said lugs being 120 beveled on their upper faces to permit the member to move past the lugs during the closing movement of the door and a spring member secured to said handle and to which the last named lug is attached.

9. The combination with a door frame and a door in said frame, of a lever pivoted to the frame, a guide fixed to the door, a member on said lever arranged to move in said guide during movement of the door, 130

means to lock the member against movement when the door is closed, means for locking the member against movement in the direction such as will open the door when the latter is in partly closed position, 5 means for releasing both of said means, and means for preventing release of said last named locking means when the door is in partly closed position, and is locked against 10 opening, comprising a cylinder on said guide, a plunger in the cylinder, a bolt mounted to slide crosswise of the plunger and connected with the releasing means, said bolt and plunger having shoulders 15 thereon which coact to prevent movement of the bolt, and spring means to hold the

plunger in up position and the shoulder in coöperative position, said plunger normally extending above the first named locking means in the path of said member on the 20 lever.

10. The combination with a door frame and a door in said frame, of means for locking the door against opening when the door is partly but not completely closed, being 25 unlocked only upon movement of the door into closed position and means for unlocking said locking means when the door is moved into closed position from said partly closed position.

HARRY BENSON.
